UNITED STATES PATENT OFFICE

2,560,153

SHIP

Luther H. Blount, Warren, R. I.

Application May 13, 1950, Serial No. 161,772

2 Claims. (Cl. 114—65)

1

This invention relates to a ship and method of constructing the same.

The usual manner of constructing a ship is to provide a frame in substantially the shape of the ship with a skin of metal plates or wooden planks secured to the frame to provide the outer shell of the ship. Rafts and some ships have been formed by utilizing barrels or cylinders but where a ship is to be driven through the water some formation is desirably provided for a bow and a stern which will be of a structure different than the blunt ends of a barrel. Also, strength must be had if cylinders are to be secured together forming parts of the ship.

One of the objects of this invention is to utilize a cylindrical construction and form the bow and stern by cutting through a formed cylindrical unit with the cut made at an angle to the axis of the cylinder and then utilizing one of the cut sections to give a desired shape to the bow while the other of the cut sections may be used to provide the desired shape of the stern, thus utilizing both parts of the cylinder in the construction.

Another object of this invention is to utilize sections cut at an angle to their axes, as indicated in the previous object, and to close these cut ends by walls which will extend beyond the cylinder cut end into meeting engagement along a center line between two such cut sections, thus forming a bow by a continuation of the wall which closes the ends of the cylinder and providing a very strong reinforced construction.

Another object of the invention is to obtain the desired bow or stern flare by rotating the cut cylinders about the cylindrical axis to dispose the angular cut as desired.

Another object of this invention is to provide a ship which will be of strong construction.

Another object of this invention is to provide a ship which is especially designed for use as a tanker, the cylinders being utilized partly for buoyancy and partly for storage of liquid to be transported.

Another object of this invention is to utilize a spacing between cylinders for carrying capacity by forming walls or bottom and deck substantially tangent to the cylindrical structures at their top and bottom portions.

With these and other objects in view, the invention consists of certain novel features of construction, as will be more fully described and particularly pointed out in the appended claims.

In the accompanying drawings:

Figure 1 is a side elevation of a ship constructed in accordance with this invention;

2

Figure 2 is a top plan view of the body of the ship with portions of the upper deck broken away;

Figure 3 is a section on line 3—3 of Figure 2;

Figure 4 is a section through one of the cylindrical structures on substantially line 4—4 of Figure 2;

Figure 5 is a diagrammatic elevation illustrating the manner of severing one of the cylindrical structures;

Figure 6 is an elevation of several cylindrical structures secured together;

Figure 7 is an end view thereof;

Figure 8 is a view similar to Figure 6 with the structure rotated through about its axis;

Figure 9 is an end view thereof; and

Figure 10 is an exploded perspective view showing the various parts which enter into the assembly of the body of the ship.

20 In proceeding with this invention I provide a plurality of cylinders which in end to end tandem relation will be substantially the length of the body of the ship and provide an additional cylinder of the same diameter as the body cylinders but which I sever at an angle to its axis which will provide the bow or stern angle desired, in some cases the angle may be 45 degrees. I then utilize one of the sections so formed as the forward end of the tandem cylinders of the body and the other end I utilize as the stern and position them in tandem relation to the cylinders of the body.

25 Two lines of cylinders thus made up with their axes substantially parallel are in spaced relation, the distance depending upon the width of the ship which is desired. Reinforcements are provided between the cylinders and a bottom is provided substantially tangent with the lower arc of the cylinders and a deck is provided substantially tangent with the upper arc of the cylinders. The bow is formed by closing the cut ends of the forward sections and carrying the wall which forms this closure from each of the cut ends forwardly with the walls converging toward each other and meeting in a center line midway between the axes of the parallelly arranged cylinders. The stern may have the ends of the cut sections similarly closed.

30 With reference to the drawings, the body of the ship is formed from cylinders 10 and 11 which for convenience of handling may be of any desired number of sections positioned with their axes substantially in line in end to end relation and secured together to provide a single cylinder of the required length for the body. Two of these lines of cylinders are positioned in parallel rela-

35 40 45 50 55

tion with their axes spaced a distance dependent upon the width of the ship to be formed. The end section of each line of cylinders is formed from a cylinder which I designate generally 12 and which is severed at an angle to its axis and which may be at such inclination as may be desired for the flare of the bow to be provided, as shown at 13 in Figure 5. In this figure I have illustrated the edges as somewhat curved, which I refer to as a pseudo dihedral although these may be severed along a plane if desired to provide a dihedral. However, in most cases I have slightly curved the formation, as shown, and then cut the other section correspondingly by cutting off the portions 15 and 16 to obtain the desired shape. These two sections then form the bow section 17 and the stern section 18 and are positioned with their right angular edges against the edges of the end sections 10 with their cut edges or faces 13 at the ends of the formation. Rotating a cut section about its axis serves to vary the direction of the flare and the direction of the closure wall for the bow and stern of the ship.

The cut ends or faces 13 are closed by side walls 26 and 27 extending across the cut ends of the bow section 17 and continuing to a junction line 28 at the middle of the ship where they join and form the bow of the ship. These walls are also carried above the section 17 so as to form bulwarks 29 or a part of a rail at the bow. A wall 30 will close the cut ends at the stern and may extend across from one cylinder 10 to the other 11 and form a transom.

Bulkheads 20 in the cross section of an I-beam having a vertical portion 21 with heads 22 and 23 are positioned between the body cylinders at intervals along its length and a bottom wall 24 is secured substantially tangent to the cylinders and onto the heads 23 of the I-beam. A deck 25 is similarly secured substantially tangent to the cylinders and to the heads 22 of the I-beams running across the body of the ship. The bottom 35 wall 24 and the deck 25 will be carried forward to meet these walls 26 and 27 and 30 in substantially the plane in which these two walls extend.

Reinforcements will be provided within the cylinders as occasion may require and also hatches 31 will be formed at intervals along the body sections which will permit entrance thereto. The body sections may be utilized for storage of liquids where their buoyancy is not required as also may the portions between bulkheads and the bottom wall and the deck be utilized for storage or for living accommodations. A pilot house 32, mast 33 and boom 34, stanchions 35, rail 36 or other super-structure may be provided on the

deck as desired. The propelling of the ship will be from the stern by a known arrangement.

Although the bottom is shown as tangent with the lower arc of the cylinders, the bottom can be flat, V'd, or rounded in accordance with intended service and desired conformity to a conventional hull shape.

I claim:

1. A ship comprising an end portion having a pair of substantially parallel spaced cylinders whose axes are in substantially a horizontal plane, said cylinders each having an open end face disposed at an angle to said horizontal plane and at an angle to the axis of the cylinder, a side wall contacting each end face and closing said cylinder and extending inwardly of the corresponding cylinder to join the opposite side wall at a distance substantially midway between said cylinders, and a bottom wall attached to said cylinders and engaging said side walls thus closing the end portion of the ship.

2. A ship comprising bow and stern end portions each portion having a pair of substantially parallel spaced cylinders whose axes are in substantially a horizontal plane, said cylinders each having an open end face disposed at an angle to said horizontal plane and at an angle to the axis of the cylinder, a side wall contacting each end face and closing said cylinder and extending inwardly of the corresponding cylinder to join the opposite side wall at a distance substantially midway between said cylinders, and a bottom wall attached to said cylinders and engaging said side walls thus closing the end portions of the ship.
